UNITED STATES PATENT OFFICE

140,292

DESIGN FOR A COMBINED DOLL AND CONTAINER

Cheri Rich and Benjamin Saffran,
New York, N. Y.

Application September 13, 1943, Serial No. 111,114

Term of patent 3½ years

(Cl. D34—4)

To all whom it may concern:

Be it known that we, Cheri Rich and Benjamin Saffran, citizens of the United States of America, residing in New York city, county of New York, and State of New York, have invented a new, original, and ornamental Design for a Combined Doll and Container, of which the following is a specification, reference being had to the accompanying drawings, forming a part thereof:

We claim:

The ornamental design for a combined doll and container as shown.

CHERI RICH.
BENJAMIN SAFFRAN.
